UNITED STATES PATENT OFFICE.

LINCOLN KING, OF NEW YORK, N. Y.

INDICATOR-LOCK.

SPECIFICATION forming part of Letters Patent No. 487,276, dated December 6, 1892.

Application filed July 27, 1892. Serial No. 441,408. (No model.)

To all whom it may concern:

Be it known that I, LINCOLN KING, a citizen of the United States, and a resident of the city of New York, in the State of New York, have 5 invented a new and useful Improvement in Indicator-Locks, of which the following is a specification.

This invention relates to knob-actuated locks or bolts especially designed for the doors 10 of water-closets, bath-rooms, dressing-rooms, and the like and combined with or adapted to coact with indicators by which it can be readily known from outside the door whether or not the room is occupied.

15 The present invention consists in certain novel combinations of parts, as hereinafter set forth and claimed.

A sheet of drawings accompanies this specification as part thereof.

20 Figures 1 and 2 of these drawings are respectively an elevation and a horizontal section showing the door locked and the indicator exposed. Figs. 3 and 4 are like views showing the door unlocked and the indicator 25 withdrawn or concealed from view. Fig. 5 is an edge view of the two parts of the lock-casing. Fig. 6 represents a section on the line 6 6, Fig. 2, showing the interior of the lock and indicating by dotted lines its use at the 30 opposite edge of the door. Figs. 7 and 8 are edge views of the two parts of the keeper, showing them, respectively, as in Figs. 1 to 4 and as attached to a door opening inwardly; and Fig. 9 is an elevation showing 35 the indicator as used at the opposite edge of the door as compared with its location in Figs. 1 to 4.

Like reference numbers and letters indicate corresponding parts in all the figures.

40 The rim-lock is composed of a horizontal bolt 10, both ends of which are alike, and which is provided with a central rack *a*, a toothed sector 11, in mesh with said rack, and a casing for these parts, consisting of a flat 45 back plate 12 and a hollow or box part 13, the latter having flanges extending to the edges of the back plate and provided in common with the latter with screw-holes, so that the parts are connected by the screws 14, 50 which attach the rim-lock as a whole to the back of the door. The respective ends of the bolt project through holes *b*, formed by notches

in said box part 13. A spindle 15, united with a knob or handle 16 at its inner end and pinned fast to said sector 11, extends through 55 the rim-lock and door and carries at its grooved outer end a reversible signal-arm 17, which is held on the spindle and masked, when the door is unlocked, by a shield or "escutcheon" 18, attached to the outside of the door 60 by a pair of screws 19.

A metallic keeper to coact with the bolt 10 is formed by means of separate flat and box pieces 20 21, (shown in edge view in Figs. 7 and 8,) which are united and attached to the 65 door-frame by a pair of screws 22, the relative positions of the parts being as in Fig. 7 in the arrangement shown in Figs. 1 to 4, or for a door opening outwardly. When the bolt 10 is projected so as to lock the door, the signal-arm 70 17 projects into view, as in Figs. 1 and 2. A quarter-turn of the handle 16 retracts the bolt and withdraws the signal-arm behind the escutcheon 18, as in Figs. 3 and 4, and a reverse movement of the handle refastens the 75 door and again exposes the signal-arm.

It is not necessary to read any word or words which may be exposed to view, the position of the signal-arm serving itself to indicate that of the bolt. The indicators of a long row of 80 doors, as in hotel and railway-depot closets, may thus be easily read at a glance. Ordinarily such indication that a room is occupied would in all cases be respected. If, however, it becomes necessary in order to expel an in- 85 truder, for example, the door may be readily unlocked from the outside by means of the signal-arm 17, used as a lever-arm to turn the spindle 15 and sector 11, so as to retract the bolt 10, said signal-arm being rigid in the di- 90 rection of the movement of the spindle and exposed so as to be readily reached by the finger when the door is locked, as in Figs. 1 and 2.

The rim-lock need simply be attached at the 95 free edge in one and the same way in applying it to right-hand or left-hand doors, as illustrated by Fig. 6 in connection with Figs. 1 to 4. The same is true of the escutcheon 18. The signal-arm 17 is reversed so as to expose 100 its other side and project in the opposite direction, as illustrated by Fig. 9 in contrast with Fig. 1. To facilitate so using the signal-arm in either position, it is loosely attached to

the outer end of the spindle 15, as shown in the drawings, by an inwardly-projecting stud *c*, Fig. 9, coacting with one or the other of two longitudinal grooves *d e* in the otherwise 5 round spindle. The outer end of the spindle and its socket in the signal-arm may be square. The spindle and its said grooves or square are made long enough to fit the greatest thickness of door, and this end of the spindle is cut off 10 to the required length in applying the lock to thinner doors.

For doors opening inwardly, instead of outwardly, the keeper 20 21 is attached in the manner represented by Fig. 8 in contrast with 15 Fig. 7, the attaching-screws 22 being reversed.

Both sides of the signal-arm 17 are preferably provided with the word "Occupied," as shown in Figs. 1 and 9. Any equivalent word or words may be used, or the signal-arm may 20 be used without any word thereon, and other like modifications will suggest themselves to those skilled in the art.

Having thus described the said improvement, I claim as my invention and desire to 25 patent under this specification—

1. An improved indicator-lock composed of a rim-lock having a horizontal bolt either end of which may be used and which has a central rack and a toothed sector in mesh with

30 said rack, a spindle provided with a knob or handle at its inner end and serving to actuate said sector, a reversible signal-arm carried by the outer end of said spindle, and an escutcheon which masks said signal-arm when the bolt is retracted, substantially as herein- 35 before specified.

2. In an indicator-lock, the combination, with the bolt mechanism and its spindle and with an escutcheon at the outer end of said spindle, of a signal-arm which is carried by 40 said outer end of the spindle, is rigid in the direction of the movement of the spindle, and projects from behind said escutcheon when said bolt is projected, and is thus adapted to be used as a lever-arm to retract said bolt in 45 case of emergencies, substantially as herein-before specified.

3. In an indicator-lock, the combination, with a rim-lock and an escutcheon adapted to be used at the free edge of either a right- 50 hand or a left-hand door and with the lock-spindle, of a reversible signal-arm carried by the outer end of said spindle, substantially as hereinbefore specified.

LINCOLN KING.
